HOLDING DEVICE

William Byrd, Jr., Princeton, N. J.

Application August 21, 1946, Serial No. 692,087

5 Claims. (Cl. 292—70)

1

The present invention relates to an improved magnetic catch for holding hinged or sliding members.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate several embodiments of the invention, and together with the description, serve to explain the principles of the invention.

Of the drawings:

Figure 1 is a view in vertical medial section of one form of door stop intended to hold a door in the full open position;

Figure 2 is a fragmentary side elevation taken along the lines 2—2 of Figure 1;

Figure 3 is a view partially in elevation and partially in section of another form of door stop embodying my invention;

Figure 4 is a view in elevation, with portions broken away for clarity of another embodiment of my invention;

Figure 5 is a view, partially in section, of the magnet assembly of Figure 4; and

Figure 6 is a view in elevation of a variation of the elements of Figure 4.

An object of my invention is to provide a magnetic door stop capable of holding a door in the fully open or closed position against forces of the magnitude produced by air currents or spring or weight devices which may be provided for closing purposes. Another object of my invention is to provide a magnetically operated friction brake for minimizing the slamming of doors and for preventing the rattling of closed doors. It will be understood from the stated objects and from the following description that a device built in accordance with my invention operates automatically to stop any further motion when a door or other movable member to which it has been applied, is moved to a limiting position, unless a force greater than the holding power of the device is applied to return the door from the limiting position.

Referring now in detail to the accompanying drawings, in Figure 1, a magnet assembly 1, is fastened to a door 2, in such a position that when

2

the door is fully opened, the working face of the magnet engages a keeper 3, carried by a common form of door stop 4, which mounts on the floor 5. The keeper and the door stop have buttonlike ends 6, 7, respectively, which engage a coupling 8, of rubber or other flexible and shock absorbing material.

The magnet 1, is composed of a cylindrical cup 9, of magnetizable material in which is mounted, coaxially, a solid cylindrical axially magnetized permanent magnet 10, of high energy alloy.

One pole face of the permanent magnet abuts the bottom of the cup, while the other pole face abuts one end of a cylindrical pole piece 11, of magnetizable material and coaxial with the cup. Since the inside diameter of the cup is greater than the outside diameter of the permanent magnet and pole piece, an annular space 12, is formed. This space contains lead or other non-magnetizable material capable of holding the permanent magnet and pole piece in their proper positions.

The pole piece and cup may be grooved circumferentially as shown at 13, 14, respectively, to prevent any possibility of the loosening of the pole piece.

Figure 2 shows the working face of the assembled magnet of Figure 1. Referring to both Figures 1 and 2, the cup provides an annular working surface 15. The pole piece 11 provides a working surface 16, in the plane of surface 15, and separated therefrom by the magnetic leakage gap 17. The pole areas 15 and 16, and the cross-section to flux and length of the permanent magnet, are so proportioned that the flux passing between the working face of the magnet and the keeper is highly concentrated when the keeper surface and magnet face are in full contact. Concentration of flux passing between area 16 and the keeper can be produced by employing a recess 18, in the working surface of the pole piece. With the keeper removed a large proportion of the flux shifts to the leakage gap 17. The area and length of the gap 17 are so designed that the total reluctance of the external circuit is such as to permit the permanent magnet material to operate at substantially its maximum energy condition when the circuit assembly is not attached to a highly permeable surface. Thus there is no tendency to demagnetization upon repeated contact and non-contact of the magnetic circuit and the keeper.

The construction of the magnet as described is highly efficient for holding purposes. It enables

an inexpensive and compact magnet to develop a tractive force which is adequate for the intended application.

Referring to Figure 3, magnet 20, is similar to, but may be somewhat larger than the magnet of Figures 1, 2. The magnet 20, is mounted on door 21, by use of a strap 22, and screws 23. The working face 24, of the magnet parallels the floor 25, and is slightly below the bottom surface 26, of the door. A plate 27, of magnetizable material is hingedly attached at pivot 28, to a plate 29, which is recessed in the floor and fixed thereto by screws 30. Plate 27, has a slightly curved portion 31, and a recessed portion 32, and is so positioned that when the door is swung toward a limiting position, either fully open or fully closed, the door and magnet face will pass immediately above it.

As the magnet passes over plate 27, attractive force causes the plate to hinge upward off the floor until it contacts the magnet face. Further motion of the door is opposed by the frictional retarding effect caused by the adherence of the plate to the magnet. A braking action is thus provided.

The recessed portion 32, of the plate 27, is so placed that it engages the magnet face 24 when the door is in its limiting right hand position. The force required to move the door to the left from this position is multiplied by the stopping effect of shoulder 33. Through adjustment of the angle of this shoulder and of the bevel of the edge of the magnet face, the force required to break the magnetic hold can be controlled.

Referring now to Figure 4, a holder 35, is fastened to the floor 36, by screws 37. Within the holder is a magnet assembly 39, resting on a cushion 40 of sponge rubber or other suitable material. The magnet assembly 39 is provided with considerable freedom of vertical motion, but cannot be pulled out the top of the holder 35 because its enlarged portion 41, will strike the constriction 43, of the holder. This construction is provided to minimize the likelihood of theft of the magnet assembly.

The top face 44, of the magnet assembly is provided with two concentric polepieces as will be described in connection with Figure 5. The holder 35, is installed in the usual position of door stops. A bracket 46, of high magnetic permeability material is mounted on the door 47, by screws 48. The bracket is so positioned that as the door swings (toward the right) to its full open position, the bracket passes directly over the face 44, of the magnet assembly.

It will be appreciated that the vertical positioning of the face 44 with respect to the bottom surface 49, of the bracket 46 is not at all critical. If face 44 is slightly higher than surface 49, the magnet assembly 39 is pushed downward and the cushion 40 slightly compressed. If on the other hand, face 44 is slightly below surface 49, attraction will cause the magnet assembly 39 to rise until face 44 attaches itself to surface 49. As soon as the magnet assembly and bracket become attached, the holder acts to prevent further motion of the door. However, further motion is still possible if sufficient force is applied to overcome the frictional resistance of sliding the bracket across the magnet face. It will be understood that as the door swings rapidly toward its full open position, the magnet assembly and keeper provide automatic braking operation, bringing the door to rest over a short distance and then holding it open until sufficient force is

exerted manually on the door to break the magnetic hold. I have found that magnet assemblies which resist the sliding of a keeper across their face with a force of the order of 5 to 15 pounds are generally very satisfactory. The construction of a suitable type of magnet assembly is shown in Figure 5 which is a half-section view of a cylindrical magnet.

Referring to Figure 5, a casing 50 of high permeability material has a cylindrical interior in which is fitted a sleeve 51 of non-magnetic material. A cylindrical permanent magnet 52, axially magnetized abuts the inside bottom surface of the casing 50 and is centrally positioned by the sleeve 51. A polepiece 53 abuts the top of the permanent magnet 52. The top portions of the casing, sleeve and polepiece provide a flat surface which contains annular poles 54, 55 separated by the gap 56. The bevel 57 and the recess 58 serve to limit the polar areas 54, 55. Concentration of the flux passing between the magnet face and an attached permeable body is thus obtained and gives the magnet assembly its high performance.

Figure 6 shows a variation of the devices of Figures 4, 5 employed to operate in the closed position of doors. In Figure 6 the magnet holder 60, is mounted on the door 61 and the bracket 62, is mounted on the frame 63, above the top of the door. The magnet assembly 64, rests on a cushion (not shown) in the holder.

It is evident that the magnet assembly can be carried by the door or attached to the wall or floor and that the bracket can be correspondingly positioned. It is possible to insert a magnetic plate in the bottom of the door to avoid use of an exposed bracket or other device serving the same purpose. When such a plate is used it is desirable to make a recess in the floor to receive the magnet assembly and holder.

The cylindrical magnet construction which I have described provides the required holding power in a compact assembly. It should be understood, however, that other designs and shapes of permanent holding magnets such as the rectangular types disclosed in my copending application Serial No. 692,086 entitled Magnetic Circuit Holding Device, filed August 21, 1946, now abandoned, may be substituted for the magnet assembly described herein. When the magnet is of rectangular shape, it will be understood that it can be retained by a box type holder or a rectangular clamping bracket.

The invention in its broader aspects is not limited to the specific mechanisms shown and described but departures may be made therefrom within the scope of the accompanying claims without departing from the principles of the invention and without sacrificing its chief advantage.

What is claimed is:

1. A magnetically loaded friction device for braking the motion of a hinged door in the region of one of its limiting positions, comprising a permanent magnet member having a polar surface and a magnetically permeable member, the polar surface of said magnet and an opposable surface of said permeable member being adapted to have frictional engagement with each other, one of said members being mounted on said door and the other member being mounted on a surface near one of the limiting positions of said door, one of said members being vertically slidably toward the other, said members being so positioned that the opposable surface of said permeable member and

the polar surface of said magnet member will be brought into adjoining relationship as the door approaches said limiting position, and will be mutually attracted into slidable frictional contact, as the door nears the limiting position at which said surface-mounted member is located, due to the magnetic attraction between said members.

2. The device of claim 1 in which said permanent magnet member comprises a magnetic circuit comprising a permanent magnet at least partially surrounded by a casing of highly permeable material, said casing being slightly spaced from said permanent magnet adjacent one pole of the permanent magnet to provide a leakage gap and a non-magnetic solid material in said gap and spacing said magnet from the surrounding highly permeable material.

3. The device of claim 1 in which one of said members is mounted on a surface near the limiting open position of said door.

4. The device of claim 1 including means for resiliently supporting said magnet member, in a position where the polar surface of said magnet member will engage the opposable surface of said permeable member to permit depression of said magnet member against resistance of said means.

5. The device of claim 1, wherein the vertically slideable member is provided with a resilient mounting urging it toward the other member, and where the contacting surfaces of the two members are disposed in overlapping horizontal planes, whereby the frictional force between the two members is due both to said resilient mounting and to the mutual magnetic attraction.
